(57) **CLAIM**

The ornamental design for “video laryngoscope blade,” as shown and described.

DESCRIPTION

FIG. 1 is a left front perspective view of a first embodiment of a video laryngoscope blade showing our new design;
FIG. 2 is a right rear perspective view thereof;
FIG. 3 is a rear view thereof;
FIG. 4 is a front view thereof;
FIG. 5 is a bottom plan view thereof;
FIG. 6 is a left side view thereof;
FIG. 7 is a top plan view thereof;
FIG. 8 is a right side view thereof;
FIG. 9 is a left front perspective view of a second embodiment of a video laryngoscope blade showing our new design;
FIG. 10 is a right rear perspective view thereof;
FIG. 11 is a rear view thereof;
FIG. 12 is a front view thereof;
FIG. 13 is a bottom plan view thereof;
FIG. 14 is a left side view thereof;
FIG. 15 is a top plan view thereof; and,
FIG. 16 is a right side view thereof.
